UNITED STATES PATENT OFFICE.

GEORGE M. CARNES, OF ROCHESTER, NEW YORK.

WHEELING AND EDGE-SETTING MACHINE.

No. 852,708.

Specification of Letters Patent.

Patented May 7, 1907.

Application filed September 6, 1905. Serial No. 277,199.

To all whom it may concern:

Be it known that I, GEORGE M. CARNES, a citizen of the United States, residing at Rochester, in the county of Monroe and State of New York, have invented certain new and useful Improvements in Wheeling and Edge-Setting Machines, of which the following is a specification, reference being had therein to the accompanying drawing.

10 This invention relates to improvements in shoe machinery, and has for its primary object the provision of a machine designed to form indentations or imitation stitch impressions upon the upper surface of the projecting portions of shoe soles, and for also simultaneously, or at a single operation, edge-setting the edges of said soles.

15 A convenient embodiment of the invention comprises a machine provided with a wheeling tool arranged to form the desired impressions, in combination with an edge-iron operatively associated with said wheel, whereby the former may operate upon the upper surface of the sole while the latter operates on the outer edge thereof.

20 Novel characteristics of a practical machine made in accordance with my invention embrace instrumentalities whereby to preserve a yielding relation between the edge-iron and indenting tool; means for adjusting the angle of the tool with respect to the edge-iron, or vice versa; means for maintaining engagement of the edge-iron with the sole under pressure; and means for variously adjusting the parts to accommodate the machine to different thicknesses of shoe soles.

25 All of the above stated as well as other novel details in the construction and arrangement of parts, will be apparent from the detailed description hereinafter contained when read in connection with the accompanying drawings forming part hereof, and wherein the before referred to convenient embodiment of the invention is illustrated.

30 In the drawings, Figure 1 is a front elevation of the machine, the lower portion of the supporting frame or column being broken away; Fig. 2 is a corresponding side elevation; Fig. 3 is a sectional view of the lower portion of Fig. 2; Fig. 4 is an enlarged detail side elevation of the co-operating wheeling and edge-setting tools and illustrative of the application of the work therebetween; Fig. 5 is a longitudinal edge view of the edge-set-

ting tool detached from the machine, and Fig. 6 is a top plan view of the same.

Referring more specifically to the drawings, wherein like reference characters refer to corresponding parts in the several views, A designates the upper portion or head of a supporting frame or column, the extreme end of this column being offset as at a to support the operating parts in proper relation, as will hereinafter appear. In this offset portion I provide a crank pin B connected and operated by a pulley C driven from any suitable source of power through the medium of a belt D. Pivoted to and leading horizontally from the crank pin B is a connecting rod or arm E pivotally connected at its inner end to a substantially vertically disposed rocking arm F, the pivot point between these two members or arms being represented at f. The rocking arm F is pivoted intermediate its ends upon a stub pintle G projecting outwardly and fixed to the face of the support A. The lower end of the rocking arm is provided with an axially disposed recess portion h bordered by two parallel flanges H, between which latter and within said recess h a carrier I is pivoted at i. The carrier is fashioned to support both a nurling wheel J and edge-iron K soon to be specifically described.

35 L is a spring arranged within a vertically disposed pocket l in the carrier I and adapted to bear upon the under surface h' or top wall of the recess h in the rocking arm F, whereby the carrier is constantly pressed downwardly and cushioned in any upward movement thereof. A tail-piece i' rigid with the carrier and located beyond the pivot i thereof restricts the downward movement of the carrier under the influence of the spring L.

40 In the lower portion of the carrier I a horizontally disposed pocket M is provided for the reception of the edge-setting tool K, said pocket in transverse section being of angular contour complementary to the shape of the said tool to prevent turning movement of the latter. The tool has an elongated shank m threaded at its rear end and passing loosely through an aperture m' communicating with the horizontally disposed pocket just referred to. Adjusting and locking nuts n n', respectively, threaded upon the shank m and abutting the rear edge of the carrier I serve as a means for adjusting the edge-iron against the expansive action of a spring N.

coiled about the shank and arranged within the pocket M. This spring exerts a constant pressure upon the edge-iron in an outward direction for pressing the guiding face thereof toward the bottom of the sole of the shoe.

The edge-iron K has a substantially vertically disposed guiding or supporting surface or edge k for engaging the bottom of a sole adjoining a forked horizontal extension k' for the reception of and through which the nurling wheel J works, the extension k' being the portion which sets the edge of the sole. The arms of this extension between which the nurling wheel works are sufficiently long to extend beyond or overlap the upper surface of the shoe sole and to overlap the sides of the wheel so that a part of the iron operates on and finishes the edge of the sole after its indentation by the wheel. A further advantage of the forked iron overlapping the edge is that soles of different thicknesses can be wheeled and edge set with the same edge-iron. If the work was always moved in one direction, the result could be accomplished with only two of the arms or extensions, but by the use of two the work can be moved back and forth in either direction and still be finished by the iron after being acted on by the wheel.

The manner of supporting the nurling wheel may now be described.

O is a forwardly arranged vertical extension or flange constituting a part of the carrier I and arranged near one side of the edge-setting tool K (see Figs. 1 and 3), and P is a cylindrical casing pivotally connected at its lower end by means of a lug p and pivot pin p' to the part O, said casing being adjustable upon its pivot through the medium of a concentrically arranged segmental slot o in said part O, and a binding nut q carried by the casing P. It is to be observed that the pivot p' just referred to occupies a plane which passes through the lower or operating teeth of the indenting wheel, whereby very little adjustment of the edge-iron is necessary when changing the angle of the wheel for soles of the same thickness. Within the casing a plunger R is arranged for longitudinal or sliding adjustment, the same having a threaded shank r protruding through the upper end of the casing and adjusted as desired by a nut r' and lock nut r² engaging said threaded shank. This plunger R is constantly pressed outwardly and downwardly by a spring S threaded about the shank r and housed by the casing P, but prevented from any rotary or turning movement by a dowel-pointed screw T freely engaging a suitable key-seat in the plunger, the key-seat being indicated at U.

The exterior shape of the indenting wheel J is preferably frusto-conical with the ribs or teeth thereof axially arranged around its pe-

riphery, and to enable the operating plane 65 of this wheel to be parallel to the longitudinal axis of the plunger R which carries the same, I bevel the head V of the plunger as at v and provide a pivot pin v' extending at right angles to and from said beveled surface 70 adapted to receive and constitute the pivot bearing for said wheel. This arrangement is clearly illustrated in Fig. 3.

An advantageous detail incident to the peculiar mounting of the nurling wheel resides in its ready removability and replacement or interchangeability with other wheels, it being noted that the wheels may be slipped on to or removed from the pivot pin v' by simply removing or adjusting a retainer W 80 having a slotted shank engaging the head of the plunger and clamped in position thereon by a binding screw Y, the free end of the retainer being offset as at Z to underlie and freely contact the outer or exposed end of the 85 wheel.

The operation of the machine may now be followed: The nurling wheel and edge-iron being preferably heated as is usual, for instance by a gas jet, (not shown) a shoe sole 90 is interposed between the two after the manner illustrated in Fig. 4 and fed manually or otherwise therethrough to present untreated portions of the sole to the tools. The operation of the crank pin B reciprocates the connecting rod E and thereby rocks the arm F upon its pivot G to impart a slight rapid oscillating motion to the carrier I and consequently to the edge-iron K and nurling wheel J, the latter being free to revolve on 100 its pivot pin during such oscillation. By this arrangement and operation it will be appreciated that the indenting and edge-setting are accomplished substantially simultaneously. The spring S relieves any excessive 105 pressure of the upper against the toothed wheel and also adapts the device for wheeling edges of different widths or extensions, it being noted that the widths of different portions of the sole extensions frequently vary 110 in the same shoe.

By means of the adjustable mounting of the plunger casing P and edge-iron K the angular relation of the nurling wheel to said edge-iron and the working space therebetween may be adjusted and preserved, whereby soles of different thicknesses may be accommodated and treated by the same machine.

The spring N serves to maintain a constant 120 compression of the sole between the nurling wheel and the edge-iron. While the spring L which is interposed between the carrier I and the rock arm F resists upward pressure of the carrier upon engagement of a sole with 125 the edge-iron, thus obtaining a yielding or cushion pressure on the work.

Having thus described the invention what

is claimed as new and desired to be obtained by Letters Patent is:—

1. In an imitation stitch indenting machine for boots and shoe soles, the combination with an indenting tool and its support, of means for securing the support in different angular positions to vary the position of the tool relative to the face of the stock, a longitudinally adjustable edge setting tool associated with the indenting tool, and means for actuating the tools in unison.
2. In an imitation stitch indenting machine, the combination with an indenting tool, and an edge-setting tool angularly arranged relative to each other, of means for yieldably maintaining the relative positions of the tools while operating on the stock, substantially as described.
3. In a machine of the character described, the combination with a longitudinally movable wheeling tool and a spring for normally forcing the same outward, of a longitudinal movable edge-setting tool, a spring for normally forcing the edge-setting tool outward, and means for positioning the working surfaces of the said tools in juxtaposition.
4. In a machine for finishing the edges of shoe soles, the combination with an indenting tool, of an edge setting tool having an edge setting projection thereon overlapping the indenting tool and arranged obliquely relative thereto.
5. In a machine for finishing the edges of shoe soles, the combination with an indenting tool, of an edge-setting tool having edge-setting projections thereon embracing the opposite sides of the indenting tool and means for actuating the tools.
6. In a machine for finishing the edges of shoe soles, the combination with the freely rotatable indenting wheel, of an edge-setting tool co-operatively positioned in relation to the said wheel and having a part of its edge-setting surface overlapping the said wheel with the line of its working surface crossing the working surface of the wheel and means for actuating the wheel and edge-setting tool.
7. In a machine for finishing the edges of shoe soles, the combination with a frame part, of a pivotally adjustable casing part, means for securing the casing part in different positions of adjustment, a frusto-conical indenting wheel, means for supporting the indenting wheel movable in the casing part and means for positioning the lower working edge of the indenting wheel in a position substantially parallel with the line of movement of the supporting means in the casing.
8. In a machine for finishing the edges of shoe soles, the combination with a pivotally adjustable casing part, a tool carrier slidably secured in said casing part, means for varying the limit of movement of the tool carrier, a wheel shaft arranged at an angle and lo-

cated on the end of the tool carrier, and an indenting wheel mounted on said shaft whereby the plane of the operating edge or part of the wheel lies substantially parallel with the longitudinal axis of the carrier thereof.

9. In a machine for finishing the edges of shoe soles, the combination with an indenting tool, of an edge iron operatively associated therewith and having an edge setting projection overlapping the indenting tool with the line of its working surface crossing that of the indenting tool and a spring for normally forcing the edge iron out toward the indenting tool.

10. In a machine for finishing the edges of shoe soles, the combination with an indenting tool, of an edge iron having a part adjacent to and overlapping the said tool and the line of its working surface crossing that of the tool, means for slidably supporting the edge iron, a spring for normally tending to move the edge iron outward and means for limiting the outward movement of the edge iron.

11. In a machine for finishing the edges of shoe soles, the combination with an indenting tool, of an edge-setting tool having its edge-setting edge in proximity to and overlapping the indenting tool, and means for adjusting the said tools relative to each other.

12. In a machine for finishing the edges of shoe soles, the combination with an independently spring pressed indenting tool and an independently spring pressed edge setting tool, having an edge setting part arranged adjacent to the indenting tool with the line of its working surface crossing that of the indenting tool.

13. In a machine for finishing the edges of shoe soles, the combination with an edge setting tool and an indenting tool, the former having an edge setting extension overlapping the indenting tool with the line of its working surface crossing that of the indenting tool.

14. In a machine for finishing the edges of shoe soles, the combination with an edge setting tool, of an indenting wheel, the former having an edge setting part overlapping the said wheel with the line of its working surface crossing that of the wheel.

15. In a machine for finishing the edges of shoe soles, the combination with an edge setting tool and an indenting tool, the former having edge-setting extensions overlapping and arranged respectively on the opposite sides of the latter.

16. In a machine for finishing the edges of shoe soles, in combination with an edge setting tool, of an indenting wheel, the former having edge - setting extensions projecting therefrom and extending beyond the wheel on opposite sides thereof.

17. In a machine for finishing the edges of shoe soles, the combination with an indent-

ing tool, of an edge-setting tool having edge-setting extensions overlapping on opposite sides the indenting tool and instrumentalities for actuating the tools back and forth whereby the operation of the edge-setting tool follows that of the indenting tool in both directions.

18. In a machine for finishing the edges of shoe soles, the combination with an edge-setting tool having separated edge-setting ex-

tensions at its end and an indenting tool located between the said extensions and yieldably supported for back and forth movement relative to the said extensions.

In testimony whereof I affix my signature in presence of two witnesses.

GEORGE M. CARNES.
